(57) **CLAIM**

The ornamental design for a wheel ornament, as shown and described.

DESCRIPTION

FIG. 1 is a side perspective view of my new wheel ornament; FIG. 2 is a front elevational view thereof; FIG. 3 is a side elevational view thereof; FIG. 4 is a top plan view thereof; FIG. 5 is a bottom plan view thereof; and, FIG. 6 is a front elevational view showing the wheel ornament as it could be used in a vehicle wheel spoke. The broken line showing of environment is for illustrative purposes only and forms no part of the claimed design.
